FIG. 6.

FIG. 7.

UNITED STATES PATENT OFFICE.

WILLIAM T. BENHAM, OF NORWOOD, AND JOHN E. DWYER, OF CINCINNATI, OHIO, AS
SIGNORS TO THE HALL'S SAFE COMPANY, OF CINCINNATI, OHIO, A CORPORATION
OF OHIO.

TIME-LOCK MEANS.

Application filed May 16, 1924. Serial No. 713,769.

This invention relates to locking means employable in safes, the term safes including vaults and the like, and relates especially to such locking means in connection with time mechanism.

It is the object of the invention to provide novel means for connecting the time mechanism with the bolt mechanism for locking the safe, arranged in such manner that the time mechanism is relieved from stresses of felonious attempts of operation of the bolt-works; further, to provide means whereby the time mechanism is separated from the bolt mechanism and the obstructing means for the latter, to remove the time mechanism from the shocks and jars incident to felonious attempts to manipulate the bolt mechanism; and, further, to provide novel arrangements of obstructing means for the bolt mechanism controlled by the time mechanism, and rigid mounting means on the door-structure for the same.

The invention will be further readily understood from the following description and claims, and from the drawings, in which latter:

Fig. 1 is a rear elevation of an exemplification of the invention, with the safe-door and the door of the time-casing partly broken away, and illustrating the device in relation ready for locking the door.

Fig. 2 is a similar view of the same, partly broken away, showing the bolt obstructing means in obstructing relation, with the bolt in locked relation.

Fig. 3 is a sectional detail of the obstructing bar and bolt, taken on the line 3-3 of Fig. 6.

Fig. 4 is a vertical cross-section of the device, taken on the irregular line 4-4 of Fig. 1.

Fig. 5 is a horizontal cross-section of the same, taken on the line 5-5 of Fig. 2.

Fig. 6 is a horizontal cross-section of the same, taken on the line 6-6 of Fig. 2.

Fig. 7 is a horizontal cross-section of a safe-door and the wall of the door-opening of a safe, partly broken away, having a device of the present invention applied thereto; and,

Fig. 8 is a cross-section of a detail, taken on the line 8-8 of Fig. 4, showing the cushion mounting for the time-clock casing.

It has been the usual practice heretofore in time lock mechanism for safes, to provide an obstructing member mounted in the time-clock casing.

In practice, the time-clock casing is comparatively frail, as see Fig. 4. Mounting the obstructing means for the bolt-works in the casing, as was the usual practice heretofore, therefore provided a comparatively frail mounting for these obstructing means, rendering distortion or displacement of the same, their mounting and the casing readily possible, and subjecting the time devices and the casing to the direct shocks and jars of the bolt-works, rendering the time devices, their casing and the obstructing means readily shiftable. Derangements of the obstructing means, of the time devices and their casing, have taken place by burglaries manipulations of the bolt-works, as by blows upon the handle of the bolt-works, attempts at manipulation of the handle by the affixing of long bars or levers thereto, pounding the axially movable bolt against the interfering part in the time-clock casing, and in other manners, resulting in shocks and jars upon the obstructing means, the time devices and their casing, so that the mounting of the obstructing means, the time devices and the time casing have been warped and bent sufficiently to permit the burglaries operation of the bolt-works to open the safe-door.

It is the object of the present invention, therefore, to provide obstructing means for the bolt-works and to so arrange and mount the same that blows and jars thereon by the bolt-works are resisted by strong members securely placed in direct relation to the door, to remove resisting connection from the time devices and the mountings of the latter, and to so arrange the parts that the sole operative connection between the time devices and the obstructing member is the holding or latching means which supports the obstructing member in obstructing relation, and to so arrange the parts that blows

and jars on the obstructing member are not detrimentally communicated to such holding means, the timing devices or the casing.

The invention is exemplified in connection with an axially movable bolt, which may be a part of any suitable bolt-works having bolts movable in one or a plurality of directions, and provided in suitable number and mounted in suitable manner, for forming proper bolting means for the door; and the door and the bolt-works may be of any suitable form, arrangement and construction.

It is to be understood that the term safe as employed in the description and claims includes safe vaults and the like; further, that the door may be suitably mounted with relation to the body of the safe either upon a hinge or hinges or in other manner to permit the movement of the door away from its closing position with relation to the door framing of the safe, and that the safe may be a fire-proof safe or a burglar-proof safe or have fire-proofing or burglar-proofing properties; that the body of the safe may be of suitable structure and have either built-up walls or walls of reinforced concrete and sheet metal, in the form of a fixed safe, sometimes termed vaults or safe-vaults, or of other suitable structure, as a movable safe, and that the body of the safe may be built up, or integral of one piece or casting, and that the joint between the door and the door-jamb or wall of the door-opening may be of suitable or usual material, construction and form.

The structures described are presented as exemplifications of desired structures, although it is obvious that changes may be made in the same and in their relations and parts without departing from our invention within the scope of the language of the appended claims.

The wall of the door-opening of the safe, which may be of any usual construction, is exemplified partly broken away at 11. A door, which may also be of any usual construction, is exemplified partly broken away at 12. The door may comprise laminated steel plates 13, in a shell 14, having an edge wall 15 which surrounds the door, connected as a rigid structure. The door is suitably hinged and arranged to be received in the door-opening 16, for closing the same, and to be locked in closed position by suitable bolt-works, operable in usual and suitable manner, one of the bolts being exemplified at 17, slidably in an inner steel flange 18 and an outer steel flange 19, which are arranged about the margin of the door. The bolts are arranged to be received in suitable holes or behind suitable locking faces 20 at the walls of the door-opening for locking the safe in usual manner. There is a suitable joint, shown as a stepped joint 21, between the door and wall of the door-opening.

The bolt-works may in the present exemplification be arranged to be locked in suitable manner by a suitable combination lock 25, or other day locking device, the locking bar or member of which is arranged to be moved into and out of obstructing relation with the bolt-works in any usual manner, for locking or unlocking the safe-door, the rotatable head 26 of the dial mechanism 27 at the outside of the door, connecting with the combination lock at the inside of the door by means of a usual stem 28.

The bolt-works may, in the present exemplification, be manipulated from the outside of the door by a suitable handle 29 at the outside of the door, which is operatively connected with the bolt mechanism at the inside of the door by a stem 30 and arm 31 having link-connection 32 with the bolt-works.

In order to control the bolt-works, suitable time mechanism 35 is provided, which may be of any usual or ordinary construction, and comprise a series of time-clocks 36, respectively provided with rotatable dials 37, having graduations of hours thereon, for instance, seventy-two hours, dependent on the number of hours for which the time mechanism is to govern.

The dials are provided with knock-out pins 38, arranged to act upon arms 39, of a slide-bar 40, slidable in the time-casing 41, of soft east brass, in which the parts are mounted. The casing is usually closed by a hinged door 53, locked by a suitable key-lock, and having a transparent lens 54 therein through which the clocks may be viewed.

The slide-bar is guided by the walls of slots 42 in the slide-bar and screws 43, the screws being shoulder-screws located between the walls of the slots and extending through the slots and threaded into the casing, the ends of the slots limiting the movements of the bar. The bar slides between the heads of the screws and the facing 44 in the casing.

The end of a pin 46 contacts an end wall in the casing, a bearing 47 on the slide-bar is received about the pin, and has a bore in which a spring 48 is located between the end of the bore and a collar 49 on the pin, for normally urging the slide-bar in one direction, to normally urge the arms thereon toward the knock-out pins of the clock-movements. A threaded plug 50 closes the bore.

The several time-clocks operate independently of one another so that any one of the knock-out pins may manipulate the bar, in order that the bar may be operated even if only one of the time-clocks remains operative.

Intermediate mechanism is provided between the bolt-works and the time-clock mechanism, arranged to be placed in obstructing relation with the bolt-works, and to be controlled by the time-mechanism, but

having its support and movement upon the safe-door, so that shocks and jars thereon may be resisted by the safe-door, and the time-mechanism be relieved from such shocks and jars and the incident detrimental effects therefrom.

In practice the time-mechanism and the casing therefor are comparatively frail in structure, as they are principally concerned in time control, and while this time control is retained in the present invention, the resistance control to opening movement of the bolt-works is removed from the time-mechanism and the casing thereof, the parts being so mounted that the safe-door resists such movements without the intervention of the time-mechanism and its casing.

The time-casing is preferably mounted on the safe-door in such manner as to be cushioned from the safe-door, effected, in the present instance, by rubber-washers 51, which are received about the screws 52 received through the back wall of the casing and into the safe-door for cushioningly holding the casing to the safe-door.

The bolt obstructing means are exemplified as a heavy obstructing bar 55 pivoted direct to the heavy structure of the safe-door, as on a shoulder-bolt 56, threaded into the rear plate 57 of the structure of the safe-door. This rear plate may be fixed to the balance of the structure of the safe-door by means of bolts 58 passing through the rear plate and pillow-blocks 59 and threaded into the balance of the door-structure, thereby forming a space 60 in which usual connecting bars for the bolt-works may operate, not shown because well-known. Rigid and massive mounting means for the obstructing bar are thus provided, as may be seen by a comparison of the heavy door-structure with the frail time-casing exemplified in Fig. 4.

The obstructing bar may be pivoted between washers 61, 62, about its pivot-bolt. It is shown guided in a slot 63 formed by a strap 64 received about the swinging end of the bar and secured to the safe-door by screws 65.

The bolt 17 is shown provided with an end slot 67 in line with a slot 68 in the lower wall of the bolt, the walls of the slots serving as guides for the swinging end of the bar, and the end of the slot 67 forming an abutment 69 for the end of the obstructing bar. The plate 57 is provided with a slot 70 to accommodate the bolt.

A lever 71 is pivoted to the bar on a shoulder-screw 72, the threaded end of which is threaded into the bar. Means are provided for normally placing the lever and the bar in coactive relation, exemplified as a parallel relation.

A spring 73 is received about a hub 74 of the lever 71, through which the shoulder-

screw 72 passes, the ends of the wire composing the spring being bent in opposite directions, one of said ends being received in a hole 75 in the bar and the other end being received in the hole 76 in the lever, for normally urging the bar and lever in opposite directions, preferably in a scissorslike movement. A pin 78 is arranged to be received in a recess 79 in the lever, and serves as a stop to limit movement between the bar and the lever urged by the spring.

A pull-pin 81 has axial movement in a bearing 82 on the lever, the end of the pull-pin being received in a hole 83 in the bar, a shoulder 84 on the pull-pin limiting the inward movement of the pin. A spring 85 between the shoulder and the lever normally urges the pull-pin toward the hole. The pull-pin is provided with a handle 86.

The lever is provided with a latch-lug 91, which is arranged to coact with the latch 92 extending from the slide-bar 40, and shown as a hook on a depending arm 93, which extends from the slide-bar in the inside of the time casing 41 through a slot 94 in the lower wall 95 of said time casing, the hook of the latch being shown outside the time casing in position for coaction with the latch-lug on the lever.

In employing my improved device, and assuming that the safe is open, the time-clocks are set for the number of hours during which the safe is to be locked, the setting being indicated by the relation of the graduations of the dial and the hand 96 of the respective clocks. It is assumed that the obstructing bar is in release position, its swinging end being at its downward limit of movement, and the bolt 17 in withdrawn or unlocked relation, extending above the outer end of the bar, as shown in Fig. 1, but with the lever 71 parallel with the bar, with the pin 81 in the hole 83.

The pull-pin is then pulled outwardly by means of its handle 86, and the lever 71 is raised to cause the latch-lug 91 thereon to be received over the hook of the latch 92 depending from the slide-bar 40 in the time-casing. The latch-lug and the latch-hook are respectively provided with sloping engaging faces 97, 98, for readily moving the slide-bar against the tension of the spring 48, the spring retracting the slide-bar for movement of the latch thereon under the latch-lug.

In this relation of the parts the spring 73 is under tension to urge the bar 55 into obstructing relation with the bolt 17, resisted by the fact that the bolt is in retracted position above the outer end of the bar.

The safe-door is now closed, and the bolt-works thereon thrown to lock the door by the usual handle 29 on the outer face of the door. The locking movement of the bolt-works causes the bolt 17 to move out

of obstructing relation with the obstructing bar 55, whereby the obstructing bar is caused to move, by the action of the spring 73 thereon, into obstructing relation with the bolt, as shown in Fig. 2. The pull-pin 81 thereby slips into the hole 83 for connecting the lever and the obstructing bar.

When the time for which the time-clocks have been set has expired, the knock-out pins 11 on the dials of the time-clocks have engaged the lugs on the knock-out bar and moved the knock-out bar lengthwise, causing the latch 92 thereon to move out of range with the latch-lug 91, whereupon the latch-lug 15 is released, and the lever 71 and the obstructing bar 55 connected therewith swing on the pivot of the obstructing bar, so as to arrange the outer end of the obstructing bar 20 into release position with relation to the bolt 17. The bolt-works may now be moved to unlock the safe-door.

In case the safe or the door or the bolt-works are subjected to any shocks or jars, such shocks or jars and the stresses incident 25 thereto are resisted by the massive structure of the obstructing-bar, the massive mounting thereof direct on the safe-door, and are not directed upon the time-mechanism or the time-casing or the mounting thereof, so 30 as to avoid derangement in the time-clock mechanism and its mounting.

The casing in which the time-mechanism is located is cushioned with relation to the door by the cushion washers 51. In the 35 present exemplification, the sole operative connection between the time mechanism and the obstructing means for the bolt-works consists of latching means between the controlled part of the time-mechanism and the obstructing means, the construction and arrangement of the parts being such that shocks, jolts or jars to which the obstructing mechanism may be subjected are not detrimentally communicated to the latching 40 means or time-mechanism.

Having thus fully described our invention, what we claim as new, and desire to secure by Letters Patent, is:

1. In time lock means of the character described, the combination of a safe-door, a 50 time-clock means comprising a casing mounted on said safe-door, latching means controlled by the latter, bolt-works for locking said safe-door, said safe-door comprising an inner plate as an integral part of said safe-door and independent of said time-clock casing, and obstructing means for said bolt-works, said obstructing means mounted on 55 said inner plate of said safe-door independent of said casing in manner that said time-clock casing is relieved from stresses produced on said obstructing means by said bolt-works and said stresses are communicated directly to said safe-door, and said

latching means arranged for operative connection with said obstructing means. 65

2. In time lock means of the character described, the combination of a safe-door, bolt-works therefor, means at the outside of said safe-door for operating said bolt-works, a 70 time-clock means including a casing mounted on said safe-door, latching means controlled by the latter, obstructing means for said bolt-works, said latching means arranged for operative connection with said 75 obstructing means, and means for mounting said obstructing means independent of said time-clock casing on the structure of said safe-door, whereby the structure of said safe-door directly receives the shocks of resistances of said obstructing means to movements of said bolt-works, and whereby said time-clock means and said casing thereof are relieved from said shocks. 80

3. In time lock means of the character described, the combination of a safe-door comprising laminated steel plates including an inner plate, bolt-works for said safe-door, a time-clock means, means for cushioningly mounting said time-clock means on said safe-door, an obstructing part for the bolt-works, means for firmly mounting said obstructing part directly on said inner plate of the structure of said door in manner to cause the safe-door to directly receive the shocks of resistances by said obstructing part and to relieve said time-clock means from said shocks, holding means for said obstructing part, and control means for the latter having operative connection with said time-clock means. 90

4. In time lock means for a safe-door, the combination with the safe-door, of bolt-works thereon, operating means outside said safe-door for operating said bolt-works, a time-clock casing, time-clocks therein, control means operated by the latter, an obstructing part outside said casing for said bolt-works, a rigid mounting therefor on said safe-door, a lever pivoted to said obstructing part, latching means between said lever and said control means, and resilient means between said lever and said obstructing part, constructed and arranged whereby to permit latching of said obstructing part to said latching means during unlocked positions of the bolts of said bolt-works and for automatically moving said obstructing part into obstructing relation with said bolt-works upon manipulation of said operating means outside said safe-door for locked positions of the bolts of said bolt-works. 100

5. In time lock means for a safe-door, the combination of bolt-works on the safe-door, a time-clock casing on the safe-door, time-clocks therefor in said casing, control means controlled by the latter, an obstructing bar for the bolt-works, a rigid mounting therefor on said safe-door, said bolt-works com- 110

prising a member provided with a cross-slot and a lengthwise slot merging into each other in which the outer end of said obstructing bar is arranged to move, a lever pivoted to said obstructing bar, latching means between said control means and said lever, releasable connecting means between said lever and said obstructing bar, and spring means between said lever and said

bar normally urging engagement in said connecting means and obstructing relation of said obstructing bar with said member during engaged relation in said latching means.

In testimony whereof, we have hereunto signed our names.

WILLIAM T. BENHAM.
JOHN E. DWYER.
